ROLL GRINDING MACHINE

Carl G. Flyare, Worcester, Mass., assignor to
Norton Company, Worcester, Mass., a corpora-
tion of Massachusetts

Application December 24, 1935, Serial No. 56,847

2 Claims. (CL. 51—95)

This invention relates to a grinding machine, and more particularly to a crowning attachment for a roll grinding machine to generate a predetermined crown on the periphery of a roll.

One of the objects of this invention is to make a simple, thoroughly practical crowning attachment for a roll grinding machine. A further object of this invention is to provide a roll crowning attachment for a roll grinding machine in which the wheel slide is rocked toward and from the axis of the roll. A further object is to provide a roll crowning attachment in which the grinding wheel is rocked toward and from the work axis in timed relation with the work table reciprocation to produce the desired crown. Another object is to provide such a crowning attachment which can be readily disconnected to permit truing of the grinding wheel while the wheel remains stationary.

A further object of this invention is to provide a roll forming attachment in which the grinding wheel slide is rocked toward and from the work axis during the relative longitudinal reciprocation therebetween, in which the crowning device may be readily disconnected to stop the rocking of the grinding wheel and may be readily connected so that the rocking motion is picked up in identically the same position prior to stopping the motion for truing.

Another object of this invention is to provide a roll crowning attachment in which the grinding wheel is rocked toward and from the work axis by a mechanism actuated by the work table reciprocation, in which backlash is entirely eliminated between the driver and the cam for rocking the wheel slide. Other objects will be in part obvious and in part pointed out hereinafter.

This invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of a grinding machine embodying this invention;

Fig. 2 is a cross sectional view through the grinding machine, on an enlarged scale, taken approximately on the line 2—2 of Fig. 1;

Fig. 3 is a fragmentary elevation, on an enlarged scale, having parts broken away to show the table traversing mechanism;

Fig. 4 is a cross sectional view, taken approxi-

mately on the line 4—4 of Fig. 3, showing the table traversing mechanism;

Fig. 5 is a fragmentary cross sectional view, on an enlarged scale, showing the backlash eliminating mechanism for eliminating the backlash between the table rack and the cross shaft;

Fig. 6 is a fragmentary sectional view, taken approximately on the line 6—6 of Fig. 2, on an enlarged scale, showing the backlash eliminating mechanism between the worm and worm gear for driving the crowning cam;

Fig. 7 is a vertical sectional view through the driving gear, on an enlarged scale, showing the means for eliminating the backlash in the gear train;

Fig. 8 is an end elevation of the backlash eliminating gear shown in Fig. 7; and

Fig. 9 is a fragmentary sectional view, on an enlarged scale, taken approximately on the line 9—9 of Fig. 8.

A roll grinding machine has been illustrated in the drawings comprising a base 10 which supports a longitudinally reciprocable work table 11 on the usual flat way 12 and V-way 13. The longitudinally reciprocable table 11 is provided with a rotatable work support comprising a motor driven headstock 16 and a footstock 17 which serve to rotatably support a roll 15 to be ground. The roll 15 may be mounted on centers, as is common practice in the art, or if the roll is very massive in construction, it may be mounted in journal rests (not shown), as shown in the prior United States patent to Norton No. 1,096,188 dated May 12, 1914, to which reference may be had for the details of the support for the work.

A rotatable grinding wheel 20 is supported on a rotatable wheel spindle 21 which is in turn supported on a wheel slide 22. The wheel slide 22 is connected by a pair of aligned studs or trunnions 23 arranged on opposite sides of the wheel slide, and which are supported on a transversely movable intermediate slide 24. The intermediate slide 24 is arranged to slide transversely on the base 10 on a pair of spaced slideways 25 (only one of which has been shown). The intermediate slide 24 is arranged to be moved transversely relative to the base 10 by means of a suitable wheel feeding mechanism. This mechanism may be of any well-known type, such as, for example, that shown in the prior United States Patent to Norton No. 762,838 dated June 14, 1904. This mechanism may comprise a half nut 28 depending from the transversely movable intermediate slide 24. The half nut 28 mates with a rotatable feed screw 29 which is journaled in bearings 35

(not shown) in the base 10. The front end of the feed screw 29 is provided with a gear 30 which meshes with a gear 31 mounted on the rear end of a rotatable shaft 32. The shaft 32 is rotatably supported in the base 10 and is provided on its front end with a gear 33 meshing with a gear 34 mounted on a rotatable shaft 35, the outer end of which supports a manually operable hand feed wheel 36. By rotation of the hand wheel 36, a rotary motion may be transmitted to the gears above described to rotate the cross feed screw 29 which serves to cause an endwise movement of the half nut 28 to feed the intermediate slide 24 and the wheel slide 22 either toward or from the work piece 15 to grind the roll 15 to a predetermined size.

In the grinding of cylindrical rolls for a rolling mill, it is frequently necessary to produce a roll which is not a true cylinder but which is provided with an outer surface which is formed either concave or convex to a deflection curve or otherwise, according to the requirements of the rolling mill. In the machine, as illustrated in the drawings, the form or crown on the roll 15 is produced by rocking the wheel slide 22 about its pivot 23 and relative to the transversely movable intermediate slide 24 as the roll 15 and grinding wheel 20 are reciprocated longitudinally relative to each other.

30 In the construction illustrated in the drawings, the work supporting table 11 is reciprocated longitudinally relative to the base 10 and the grinding wheel 20 to traverse the roll being ground past the operative face of the grinding wheel 20. 35 The table 11 is provided with a depending rack bar 40 by which the table may be traversed by a manual or power traverse mechanism, such as that shown in the prior United States patent to Norton No. 762,838 dated June 14, 1904. This 40 mechanism has not been shown in detail, since it is not considered part of the present invention; and reference may be had to the above-mentioned patent for details of disclosure.

45 A gear 41 meshes with the rack 40 and is mounted on a rotatable shaft 42 which may be rotated manually by means of a gear 43 mounted on the outer end of the shaft 42. The gear 43 meshes with a gear 44 rotatably mounted on a stud 45. A manually operable traverse wheel 46 is mounted on a hub of the gear 44 and connected thereby, by means of which the table 11 may be traversed longitudinally of the base 10 through the gear 44, the gear 43, the shaft 42 and the gear 41 meshing with the rack bar 40.

50 The table 11 may be reciprocated longitudinally by a power operated mechanism, as shown in the prior patent above referred to. This mechanism may comprise a rotatable power driven shaft 50 which is driven by a multiple speed drive contained within the casing 51, details of which have not been shown in the present case since they are not considered part of the present invention. For details of this mechanism, reference may be had to the above-mentioned prior patent. The 55 rotatable shaft 50 drives a clutch member 51 which is arranged to engage either the clutch member 52 or the clutch member 53 which are formed integral with bevel gears 54 and 55 respectively. The bevel gears 54 and 55 mesh with a large bevel gear 56 mounted on the front end of a rotatable shaft 57. The large bevel gear 56 is rotated in either direction, depending upon the engagement of the clutch member 51 with either the clutch member 52 or 53.

75 The clutch member 51 may be shifted in the

usual manner by means of a reversing lever 60 which is actuated by reverse dogs 61 and 62 which are adjustably supported in a T-slot 63 on the front of the work table 11. The reverse lever operates through a load and fire mechanism 64 to control the movement of the clutch 51 to control the direction of reciprocatory movement of the table 11.

The shaft 57 carries a gear 70 which meshes with a gear 71 mounted on a shaft 72. The shaft 10 72 also carries a gear 73 which meshes with a gear 74 mounted on the shaft 42.

In order that the power reciprocation of the table 11 may be disconnected, a clutch member 75 is interposed between the gear 71 and the gear 73. When the clutch is in the position illustrated in Fig. 4, the power reciprocation of the table is disconnected. A yoked member 76 engages the clutch member 75 and is supported by a longitudinally movable shaft 77 which is actuated by a lever 78 on the front of the machine base. When the lever is rocked toward the machine base, the shaft 77 is moved toward the left, as viewed in Fig. 4, to move the clutch member 75 in the same direction to engage it with a clutch member 79 which is formed integral with the gear 73. When the clutch member 75 is moved into engagement with the clutch member 79, the power rotation of the gear 71 is transmitted through the gear 73, the gear 74, the 30 pinion 41, to the rack 40 to reciprocate the table 11 longitudinally relative to the base 10. For further details of disclosure as to the manual or power traverse of the table 11, reference may be had to the disclosure in the above-mentioned 35 prior patent to Norton.

In order to produce a predetermined rocking motion of the wheel spindle 22 to rock the grinding wheel 20 toward and from the axis of the roll 15, it is desirable to provide a mechanism 40 to time the rocking motion of the wheel with the longitudinal relative reciprocation between the wheel 20 and the roll 15. This is preferably accomplished by providing a gear 90 which meshes with the table driving rack 40 on the under side 45 of the table 11. The gear 90 is mounted on a rotatable shaft 91 which is journaled in bearings in the base 10 of the machine. The rear end of the shaft 91 is provided with a gear 92 meshing with a gear 93 mounted on a rotatable shaft 94. The shaft 94 also carries a gear 95 which meshes with a gear 96 mounted on a rotatable shaft 97. The shaft 94 and the gears 93 and 95 carried thereby are supported on a swinging arm 98 which is supported to rotate on the shaft 91. 55 This permits the gear 96 to be changed when desired and the gear 95 to be swung into proper mesh with the gear 96 and locked in mesh therewith by a clamping screw 99 which passes through the bracket 98 and is threaded into a 60 portion of the base 10. The outer end of the shaft 97 is preferably formed as a splined shaft 100 which passes through a correspondingly shaped aperture within a worm 101 which is rotatably supported within a gear casing 102. The gear casing 102 is rigidly fixed to the transversely movable slide 24. The worm 101 meshes with a worm gear 103 mounted on a transverse shaft 104 journaled in bearings 107 and 108 within the gear casing 102. The shaft 104 supports a rotatable cam 110 which is arranged to engage a rotatable follower roller 111 which is keyed to a stud 112. The stud 112 is rotatably supported in bearings 113 and 114 which are held 75

in a casing 116 which is rigidly fixed to the rocking wheel slide 22.

The gear casing 102 is provided with an upwardly projecting stop surface 116 which is arranged to be engaged by an adjustable screw 117 which is threaded into a bracket 118 which is fastened to the rear end of the rocking wheel slide 22. If it is desired to hold the wheel slide against rocking motion, the screw 117 may be adjusted to raise the rear end of the wheel slide 22 so that the follower roller 111 is raised from operative engagement with the cam 110, so that even though the cam 110 is rotated by the longitudinal movement of the work table 11, no rocking motion will be transmitted to the wheel slide 22.

In order that the roll being formed may be accurately ground to a predetermined crown, it is essential that the grinding wheel 20 and its supporting slide 22 be rocked through an identical path when the table 11 is reciprocated in either direction. Due to the backlash in the gear drive, this is a difficult problem since when the table is reciprocated longitudinally in one direction, the backlash in the gear connection between the table rack and the cam for rocking the wheel slide will be taken up and the wheel will be moved through one path and when the table is reversed in its direction of movement by the shifting of the reverse lever 60, the change in direction of the movement of the rack 40 serves to first take up the backlash in the gear drive between the rack 40 and the cam 110 before the rocking movement of the wheel slide starts in the reverse direction, thus providing a variable which serves to cause the grinding wheel to rock in a different path on its stroke in opposite directions. In order to eliminate this difficulty, a series of backlash eliminators have been provided to take up the backlash between the worm 101 and the cam 110 and to eliminate any backlash in the gear train 92, 93, 95, 96, thus eliminating lost motion so that when the table 11 is moved in either direction, an identical rocking motion is transmitted to the grinding wheel 20 when the roll 15 and table 11 are reciprocated in either direction.

In order to eliminate the backlash between the rack 40 and the gear 90, a suitable mechanism is provided. The gear 90 is keyed by a key 120 to a sleeve 121 which is rotatably supported on a reduced portion 122 of the shaft 91. The sleeve 121 is rotatably journaled in bearings 123 and 124 which are fixed to the base 10 so as to provide a fixed rotary support for the sleeve 121. The sleeve 121 is provided with a plurality of slots 125 at its left-hand end, as shown in Fig. 5, and the outer surface of this end of the sleeve is tapered to mate with an internal conical surface 126 within a rotatable sleeve 127 mounted on a further reduced end portion 128 of the shaft 91. The sleeve 127 is slidably keyed to the shaft 128 by a key 129. The sleeve 127, when moved toward the right as viewed in Fig. 5, contracts the split end of the sleeve 121 and clamps it securely to the reduced portion 122 of the shaft 91.

To readily adjust the sleeve 127, a nut 130 is rotatably mounted on a reduced portion 131 of the shaft 91 and is held in place thereon by means of thrust washer 132. Thrust washer 133 is interposed between the inner surface of the nut 130 and the shoulder on the reduced portion 131 of the shaft 91. A pair of nuts 134 and 135 serve to lock the nut in adjusted position on the portion 131 of the shaft 91 so that it is free to rotate thereon but has no endwise movement relative

thereto. The nut 130 is provided with a cup-shaped extension 136 toward the right, as viewed in Fig. 5, which is provided with an internal thread 137 meshing with a threaded portion 138 on the sleeve 127. It will be readily apparent from the foregoing disclosure that when the nut 130 is rotated while the shaft 91 is held stationary by applying a wrench to an end portion 146 thereof, rotation of the nut 130 serves through the threads 137 and 138 to cause an endwise movement of the sleeve 127 either to clamp or unclamp the sleeve 121 to the portion 122 of the shaft 91.

In order to eliminate the backlash, a gear 145 is rotatably mounted on the sleeve 121 and is of the same size and having the same number of teeth as the gear 90. The gear 90 is provided with a plurality of projecting lugs 146 which are arranged to be engaged by a plurality of lugs 147 projecting from the gear 145, the contacting faces of the lugs 146 and 147 being at an angle to the axis of rotation thereof and at an angle slightly greater than the angle of repose. The gear 145 is urged toward the right, as viewed in Fig. 5, by a plurality of springs 150 which extend in apertures 151 in the hub of the gear 145 and are interposed between the gear 145 and a collar 152 adjustably positioned on the sleeve 121. The collar 152 may be adjusted longitudinally relative to the sleeve 121 by means of the threaded collars 153 and 154. By adjusting the collar 152 along the sleeve 121, the tension of the spring 150 may be varied so that the springs cause the surface 147 to slide on the surface 146 so that any lost motion between the gear 90 and the rack 40 is taken up by the rotation of the gear 145 due to the angular thrust of the lugs 146 and 147. The collar 152 is provided with a pin 156 which fits loosely within an aperture or hole 157 in the hub of the gear 145, so that the gear 145 can rotate relative to the collar 152. By varying the tension of the springs 150, the opposed thrust of the two gears 90 and 45 may be varied so as to eliminate any lost motion and to exert the desired pressure of the gears 145 and 90 on the rack 40 so that the shaft 91 is rotated in unison with the rack 45 when the rack moves in either direction to rotate the gear 90.

A similar backlash eliminating device is provided between the worm wheel 103 and the cam 110. As illustrated in Fig. 6, the worm gear 103 is formed in two halves. The part 103 is connected by a key 160 to the shaft 104. The half 161 of the worm gear 103 is rotatably mounted on the shaft 104 and is provided with an outwardly projecting lug 162 which engages a correspondingly shaped lug 163 which is formed as an integral part of the collar 164 which is slidably keyed to the shaft 104 by a key 165. The collar 164 is urged toward the right, as viewed in Fig. 6, by a plurality of springs 166 which are contained within apertures 167 in the collar 164 and which bear against an adjustable collar 168. The collar 168 may be adjusted longitudinally on the shaft 104 by the adjusting collars 169 and 170. A pin 171 is fixed to the collar 168 and slides within an enlarged aperture or hole 172 within the collar 164 so that the collar 164 can rotate relative to the collar 168. By adjusting the position of the collar 168, the tension of the springs 166 may be adjusted, so that the lugs 162 and 163 cause the gear section 161 to be rotated relative to the worm gear part 103 which is keyed to the shaft so as to eliminate any backlash between the worm wheel 103 and the worm 101.

A further backlash eliminating device is pro-

vided in the gear train 92, 93 to eliminate any backlash or wear between said gears. As illustrated, the gear 92 is formed as a two-part gear. Gear 92 is keyed to the shaft 91 by a key 180. A second part of the gear 92 is formed as an annular ring 181 having teeth cut therein to mate with the teeth of the gear 91. The ring gear 181 fits on a hub portion 182 of the gear 92 and may be locked thereto by clamping screws 183 and 184 which pass through elongated slots 185 and 186 in the gear ring 181 and are screw threaded into the gear 92.

In order to eliminate the backlash between the gears 92 and 93, it is necessary to adjust the ring gear 181 relative to the gear 92. To facilitate adjustment of the gear 181 relative to the gear 92, the gear ring 181 is provided with a pair of diametrically opposed conical surfaces 187 and 188 which are countersunk into the outer surface of the gear 181. A pair of screws 189 and 190 pass through the conical apertures 187 and 188 and are screw threaded into the gear 92. Each of the screws 189 and 190 is provided with a conical surface 191 which is shaped so that an element of its surface coincides with an element of the conical counterbored surface 187 or 188. To adjust the gear ring 181 relative to the gear 92, the screws 183 and 184 are loosened and then by slackening off on the screw 190 and tightening the screw 189, the ring gear 181 may be moved in a counterclockwise direction relative to the gear 92 to eliminate the backlash between the gears. When the required adjustment has been made, the ring gear 181 and the gear 92 are clamped together by tightening the screws 183 and 184.

The tumbler gear 95 may be adjusted to mesh to a greater or lesser extent with the gear 96 by swinging the bracket 98 so that the backlash between these two gears may be eliminated.

It will thus be seen that a driving mechanism has been provided which serves to rock the grinding wheel 20 through a predetermined path when the table 11 is reciprocated longitudinally and moves in either direction to produce a predetermined concave or convex crown upon the roll being ground, depending upon the nature of the cam 110 which is mounted on the machine.

It may be desirable during the truing operation to disconnect the crowning attachment so that the wheel 20 may be trued while it remains stationary, that is with the rocking movement thereof stopped. This is preferably accomplished by unlocking the sleeve 121 from the shaft 91. It is desirable that the crowning attachment be disconnected in such a way that after a wheel truing operation, the crowning attachment may be picked up when the table is in a predetermined position so that the grinding operation on the roll being ground may be continued and the desired crown produced after the truing operation has been completed. In the preferred construction, an index finger 200 is fixed to the table 11 and is arranged to be aligned with a fixed point 201 projecting from the base 10. An indexing finger 202 similarly projects from the base 10 and is arranged to serve as an index for a graduated scale 203 arranged on the periphery of the sleeve 127. To disconnect the crowning attachment for truing so that the crowning movement of the wheel may be picked up at the same point after truing, the table 11 is traversed until the index finger 200 is aligned with the fixed point 201 on the base 10. The reading of the scale 203 opposite the finger 202 is then noted and the sleeve 127 then withdrawn to disconnect the sleeve 121 to stop the

rocking movement of the grinding wheel during the truing operation. After the grinding wheel 20 has been trued to the required extent, the table is again moved so that the index finger 200 is aligned with the fixed index point 201 on the base 10 and a wrench is applied to the projection 140 of the shaft 91 to rotate the shaft 91 and the sleeve 127 until the predetermined graduation on the scale 203 coincides with the index finger 202 at which point the sleeve 120 is rotated to move the sleeve 127 toward the right, as viewed in Fig. 5, to clamp sleeve 121 to the shaft 91 and thereby start the crowning movement of the grinding wheel in identically the same position as prior to the truing operation.

The operation of this machine will be readily apparent from the foregoing disclosure. The table dogs 61 and 62 are adjusted to the desired position to permit a reciprocation of the roll 50 to pass the face to be ground across the periphery of the grinding wheel 20. The change gear mechanism on the rear of the machine is then adjusted to the proper gear ratio for producing a crown of the predetermined extent. A roll to be ground is then placed either on centers on the machine or, as above stated, on journal rests (not shown). The roll is then rotated and the reciprocation of the table 11 started and the grinding wheel 20 is fed into grinding relation with the roll 15 by manipulation of the manually operable feed wheel 36. The grinding operation may then be continued until the roll has been ground to a predetermined crown and finished.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. A roll grinding machine comprising a base, a longitudinally movable work supporting table thereon, a rotatable work support on said table, means including a rack to reciprocate said table longitudinally, a transversely movable slide, a rotatable grinding wheel, a support for said wheel, pivotal connections between said support and slide, a rotatable cam, a shaft supporting said cam which is rotatably mounted on said slide, a follower roller rotatably mounted on the wheel support and arranged to engage said cam, a worm and worm gear supported on said slide and arranged to rotate said cam, means to eliminate the backlash between the worm and worm gear, a rotatable shaft in the base, gear connections between the table rack and said shaft whereby the shaft is rotated when the table is reciprocated, a backlash eliminator associated with said gearing, change gears connecting the other end of said shaft and said worm, and means to eliminate backlash in said change gears so that the rocking movement of the wheel slide is accurately synchronized with the table reciprocation so as to produce a predetermined crown on the roll being ground.

2. A roll grinding machine comprising a base, a longitudinally movable work supporting table thereon, a rotatable work support on said table, means including a rack to reciprocate said table longitudinally, a transversely movable slide, a ro-

tatable grinding wheel, a wheel spindle to support said wheel, a support for said wheel and spindle which is pivotally mounted on said slide, a rotatable cam mounted on the end of said slide, a follower roller arranged to engage said cam and supported on said wheel support, driving connections between the table rack and said cam whereby the cam is rotated in synchronism with the table reciprocation so as to rock the wheel sup-

port and produce a predetermined crown on the roll being ground, means to disconnect said driving connections to stop the rocking motion of the wheel, and means including a graduated scale and index to connect said driving connections so that the wheel is rocked in the same predetermined path after truing of the grinding wheel.

5

CARL G. FLYGARE.
